UNITED STATES PATENT OFFICE.

JOSEPH P. PRESTON, OF IRVINGTON, NEBRASKA.

SAFETY POCKET ATTACHMENT.

SPECIFICATION forming part of Letters Patent No. 307,797, dated November 11, 1884.

Application filed April 5, 1884. (No model.)

To all whom it may concern:

Be it known that I, JOSEPH P. PRESTON, a citizen of the United States, residing at Ir- 5 vington, in the State of Nebraska, have invented certain new and useful Improvements in Safety Pocket Attachments, of which the following is a specification, reference being had therein to the accompanying drawings.

The object of my invention is to provide a 10 cheap and simple means for securing a pocket-book or other articles of value in the pocket of the owner in such a manner that the said articles may be quickly secured in the pocket and as quickly removed by the wearer of the 15 garment, but not by others—such as thieves or pickpockets—without the knowledge of the owner.

Another object of my invention is to prevent a pocket-book or the like from leaving 20 the pocket of a person by the jolting and vibratory movement of a vehicle in passing over rough roads.

My invention may be applied to any article 25 of a sufficient size to be carried in the pocket, but is more especially adapted to pocket-books and porte-monnaies, as from its peculiar construction and arrangement of parts it may be readily applied to pocket-books of various sizes and bulk without puckering or disfiguring 30 the appearance of the garment.

In the accompanying drawings, to which similar letters of reference are made indicating corresponding parts, Figure 1 is a representation of a sectional view of a pocket, 35 showing my invention applied in connection with a pocket-book. Fig. 2 is a side view of a clamping device removed from the pocket and pocket-book.

In the said drawings, the letter A indicates 40 the pocket of a garment, to the inner wall or lining of which I secure at a suitable interval two buttons or studs, a, to receive, respectively, the eyes of a strap or bar, B, which may be allowed to remain in the pocket of a 45 garment on which my invention is to be used, but is so constructed that the loops or eyes may be slipped over the buttons and the strap entirely removed from the pocket when de- sired.

C indicates the clamping device, which consists of two flat bars or plates, b, having their flat sides arranged parallel with relation to each other, and provided near their ends with aligned holes or perforations c, through which are inserted threaded bolts d, which may be headed at one end, and provided at the opposite end with thumb-nuts, as shown, whereby the bars or plates may be brought together to clamp a pocket-book or other articles of various sizes or bulk. To one of these plates b, 55 about midway its length, I secure by means of a swivel a short arm, e, and to the outer end of this arm I hinge another arm, f, of greater length, the object being to allow the device, when inserted into the pocket, to occupy the smallest possible space.

The clamping device, when in a pocket, will form a rectangular parcel of flat contour. The outer end of the arm f is provided with an eye, as shown, to receive one of the chain-links g, which carries a snap-hook, D, which is designed to engage the button-band or strap when the device is inserted into the pocket.

From the foregoing description the advantages and operation of my invention will be 70 obvious. The device is simple in construction, and may be manufactured at a very small expense.

Having thus described my invention, what I claim as new, and desire to secure by Letters 75 Patent, is—

The combination, with a garment-pocket having two studs or buttons, arranged as described, of the strap or bar having a button-hole at opposite ends, the snap-hook and 80 chain, the clamping device consisting of the plates having perforations near their opposite ends, the threaded bolts, thumb-nuts, and swiveled hinge-bar, all adapted to operate substantially as and for the purposes specified. 90

In testimony whereof I affix my signature in presence of two witnesses.

JOSEPH P. PRESTON.
